DESIGN FOR A NUT CRACKER

William Henry Ammon, Los Angeles, Calif.

Application May 27, 1933. Serial No. 48,222

Term of patent 3½ years

To all whom it may concern:

Be it known that I, WILLIAM HENRY AMMON, a citizen of the United States and resident of Los Angeles, California, have invented a new, original, and ornamental Design for a Nut Cracker, of which the following is a specification, reference being had to the accompanying drawing, forming a part hereof.

The figure is a perspective of the nut cracker, showing my new design.

I claim:

The ornamental design for a nut cracker, substantially as shown.

Signed at Los Angeles, California, May 22nd, 1933.

WILLIAM HENRY AMMON.
